ELECTRON DISCHARGE DEVICE

Ernest G. Linder, Princeton, N. J., assignor to
 Radio Corporation of America, a corporation
 of Delaware

Application February 7, 1945, Serial No. 576,549

10 Claims. (Cl. 250—27.5)

1

My invention relates to electron discharge devices, particularly to magnetrons useful at ultra high frequencies.

In certain types of magnetrons the anode is of the tuned tank circuit type enclosed within the envelope of the device. The anode, which may be in the shape of a U, provides at its open ends the anode segments surrounding the cathode. Thus in this arrangement the ends of the circuit removed from the anode segments are short circuited so that a voltage node is produced at this point and a voltage maximum at the open ends of the legs where the anode segments are positioned.

It is an object of my invention to provide a magnetron of improved design and useful at ultra high frequencies.

A further object of my invention is to provide such an improved magnetron of the internal tuned circuit type.

More particularly it is an object of my invention to provide a magnetron of the internal tuned tank circuit type having an improved type of tank circuit.

The novel features which I believe to be characteristic of my invention are set forth with particularity in the appended claims, but the invention itself will best be understood by reference to the following description taken in connection with the accompanying drawing in which Figure 1 is a side elevation view of a magnetron made according to my invention, Figure 2 is a view turned 90° with respect to Figure 1, Figure 3 is a longitudinal section of Figure 2, Figure 4 is a transverse section along the line 4—4 of Figure 1, and Figure 5 is an enlarged perspective of the anode tank circuit made according to my invention.

A magnetron made according to my invention is provided with the usual evacuated envelope 10 provided with press 11 from which extend support and lead wires 12, 13, 14 and 15.

Supported at the upper ends of the lead and support wires 12 and 15 is a filamentary cathode 16. These support wires also serve as leads for the heating current. An anode 17 made according to my invention surrounds the cathode and is supported by the lead 14. A shield 18 surrounding the anode is provided with apertures through which the cathode filament extends. This shield acts as an end shield as described in an article "Description and characteristics of the end plate magnetron," by Ernest G. Linder in the Proceedings of the Institute of Radio Engineers, April 1936, page 633. The function of the end plates is to withdraw electrons from the cathode-anode space at an optimum rate. The wires 19 and 20 are electrically connected to the anode by means of the leads 19' and 20' and may be utilized as a transmission line or a part of a Lecher wire system. The usual getter 9 is used.

2

In accordance with my invention and as shown in greater detail in Figure 5, I make the anode tank circuit 17 in the form of an L-shaped element having a slot 21 extending entirely through one leg and partially into the other leg thereof and having opposed arcuate shaped surfaces on the opposed inner faces of the spaced leg portions 22 and 23 to provide a cylindrical central chamber along the axis of which the cathode 16 is supported. The leads 19' and 20' are connected to the leg portions 22 and 23, which provide parallel elongated anode segments of the magnetron. A magnet having poles 25 and 26 provides the magnetic field between cathode and anode segments. Thus the elongated anode segments 22 and 23 have an integral conducting loop joining the segments at one end thereof, the loop and the length of the segments determining the electrical length of the tank circuit. With the arrangement shown, the voltage maximum appears near the ends of anode segments 22 and 23 removed from this conducting loop.

With the arrangement shown, a tube of relatively small diameter may be utilized, thus permitting the use of a small magnet. This construction enhances the action of the end plates, renders them more effective and increases the efficiency of the device, since electron emission to ineffective sections of the anode is prevented.

In one form of device designed to operate from 3 to 4 centimeters, the anode segments measured .160 inch and the leg forming the conducting loop measured .245 inch in length. Voltages on the anode varied from 590 to 790 volts.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

- An electron discharge device having an anode comprising an L-shaped member having a slot extending entirely through one leg and partially into the other providing a pair of oppositely disposed L-shaped elements, one pair of oppositely disposed elements being joined together at one end, the other legs of said elements being spaced apart and providing oppositely disposed anode segments and cathode means adjacent said anode segments for providing electrons in the space between the anode segments, and means adjacent said anode segments for providing a magnetic field between said anode segments and parallel to the legs forming said anode segments.

2. An electron discharge device having an anode comprising an L-shaped member of rectangular transverse section and having a slot extending entirely through one leg and partially into the other providing a pair of oppositely disposed L-shaped elements, one pair of oppositely disposed elements being joined together at one end, the other legs of said elements being spaced apart and providing oppositely disposed anode segments and cathode means adjacent said anode segments for providing electrons in the space between the anode segments, and means adjacent said anode segments for providing a magnetic field between said anode segments and parallel to the legs forming said anode segments, the opposing surfaces of said anode segments being concave.

3. An electron discharge device including a pair of L-shaped elements having two pairs of oppositely disposed registering parallel legs one of said pairs of oppositely disposed legs being connected together at one end, the other pair of oppositely disposed legs being spaced apart and having oppositely disposed concave surfaces and providing anode segments enclosing a space, cathode means adjacent said anode segments for providing electrons within said space and means adjacent said anode segments for providing a magnetic field along the axis of said space and within said space.

4. An electron discharge device including a pair of oppositely disposed registering L-shaped elements, one of the pairs of oppositely disposed legs of said L-shaped elements being connected together at one end, the other pair of oppositely disposed legs being spaced apart and having oppositely disposed concave surfaces and providing anode segments enclosing a space, cathode means adjacent said anode segments providing electrons within said space and means adjacent said anode segments for providing a magnetic field along the axis of said space and within said space, and a shield surrounding the anode segments.

5. An electron discharge device including a pair of oppositely disposed elongated elements in parallel spaced relationship and providing anode segments, and a conducting loop connected between said elements at one end only thereof and lying transversely to the longitudinal axis of said elements, cathode means adjacent said anode segments for providing electrons within said space between said elements and means adjacent said anode segments for providing a magnetic field within said space and parallel to the longitudinal axis of said elements.

6. An electron discharge device including a pair of oppositely disposed elongated elements in spaced parallel relationship and having oppositely disposed concave surfaces providing anode segments, and a conducting loop connected between said elements at one end only thereof and lying transversely to the longitudinal axis of said elements, cathode means adjacent said anode segments for providing electrons within said space between said concave surfaces and means adjacent said anode segments for providing a magnetic field within said space and parallel to the longitudinal axis of said elements.

7. An electron discharge device including an L-shaped conducting member, said L-shaped conducting member having a rectangular transverse section and a slot extending through one of the legs thereof and partially into the other leg whereby oppositely disposed leg portions are pro-

vided, the opposing surfaces of said leg portion providing a chamber having a circular transverse section and said leg portions providing anode segments, a cathode lying along the axis of said chamber, and means adjacent said anode segments for providing a magnetic field parallel to said cathode and between said cathode and said opposing surfaces.

8. An electron discharge device including an L-shaped conducting member, said L-shaped conducting member having a rectangular transverse section and a slot extending through one of the legs thereof and partially into the other leg of said legs whereby oppositely disposed leg portions are provided, the opposing surfaces of said leg portions providing a chamber having a circular transverse section and said leg portions providing anode segments, a cathode lying along the axis of said chamber, means adjacent said anode segments for providing a magnetic field parallel to said cathode and between said cathode and said opposing surfaces, and a shield surrounding said anode segments.

9. An electron discharge device including a tuned tank circuit comprising a pair of oppositely disposed spaced L-shaped members, said members being connected together at the outer end of one leg thereof, the other legs of said members being spaced apart and having arcuate shaped opposing surfaces providing a chamber having a circular transverse section, said spaced legs providing anode segments, a cathode mounted axially of said chamber between said arcuate shaped surfaces and means adjacent said anode segments for providing a magnetic field parallel to said cathode and between said cathode and said arcuate shaped surfaces, and a lead connected to each of said spaced legs adjacent the free ends thereof providing a transmission line.

10. An electron discharge device including a tuned tank circuit comprising a pair of oppositely disposed spaced L-shaped members, said members being connected together at the outer end of one leg thereof, the other legs of said members being spaced apart and having arcuate shaped opposing surfaces providing a chamber having a circular transverse section, said spaced legs providing anode segments, a cathode mounted axially of said chamber between said arcuate shaped surfaces and means adjacent said anode segments for providing a magnetic field parallel to said cathode and between said cathode and said arcuate shaped surfaces, and a lead connected to each of said spaced legs adjacent the free ends thereof providing a transmission line, and a tubular conducting member surrounding said anode segments providing an end shield.
